(57) **CLAIM**

I claim the ornamental design for an EvoPEX connector removal tool, as shown and described.

DESCRIPTION

FIG. 1 is a front perspective view of the invention showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a top view thereof, wherein the broken line showing of the hand is included for purposes of environment and forms no part of the claimed design.
